H. J. TRARES.

DEMOUNTABLE RIM.

APPLICATION FILED MAR. 17, 1914. RENEWED APR. 29, 1916.

1,193,088.

Patented Aug. 1, 1916.

UNITED STATES PATENT OFFICE

HENRY J. TRARES, OF EDWARDSVILLE, ILLINOIS.

DEMOUNTABLE RIM.

1,193,088.

Specification of Letters Patent.

Patented Aug. 1, 1916.

Application filed March 17, 1914, Serial No. 825,389. Renewed April 29, 1916. Serial No. 94,509.

To all whom it may concern:

Be it known that I, HENRY J. TRARES, a citizen of the United States, and resident of Edwardsville, Madison county, Illinois, have invented certain new and useful Improvements in Demountable Rims, of which the following is a specification containing a full, clear, and exact description, reference being had to the accompanying drawings, forming a part hereof.

My invention relates to improvements in demountable rims, and the object of my invention is to construct a felly band which is arranged to be permanently secured to the felly and is provided with annular inclined shoulders and segmental channels arranged to receive locking pins on a rim, the ends of said channels being inclined or chamfered in directions which will bring said rim to frictionally engage with said shoulders, and a removable locking device to prevent relative rotation of the rim and felly band, the one flange of the rim being removable in order to permit the detaching of the tire, said removable flange being provided with pins substantially of the same design as is carried by the rim for engagement with the felly band, whereby said flange may be quickly and easily removed for the detachment of the tire or the rim removed, as is common with demountable rims.

With the above purposes in view, my invention consists in certain novel features of construction and arrangement of parts as will be hereinafter more fully described, pointed out in the claim and illustrated in the accompanying drawings, in which—

Figure 1 is a fragmental elevation of a wheel constructed according to my invention, a portion of the felly being shown in section; Fig. 2 is an enlarged transverse sectional elevation taken through a felly, felly band, the separable rim and a pneumatic tire; Fig. 3 is an elevation on a reduced scale, showing my improved rim; Fig. 4 is an elevation on a reduced scale, showing my improved detachable rim flange; Fig. 5 is a fragmental plan, showing the chamfered ends and stops in the channeled rim flange; Fig. 6 is a fragmental sectional elevation showing means for securing the rim flange against rotary movement relative to the rim; Fig. 7 is a fragmental elevation showing the means for securing the rim against rotation relative to the felly band; and Fig.

8 is a fragmental plan illustrating the removable plate which covers the slot in the felly and band and the valve cap for holding said plate.

Referring by numerals to the accompanying drawings: 10 designates a felly, which may be of any desired construction.

11 designates a felly band, which is arranged to be permanently secured in any desired manner to the peripheral face of the felly band. On the periphery of said band next adjacent its inside margin, is an inclined annular shoulder 12, and on the outside margin there is an inclined shoulder 13 formed by beveling or chamfering the margin of the band. Interjacent said shoulders there is formed in the periphery of the band an annular depression 14.

15 designates the rim, having on its inner perimeter a plurality of projections 16, arranged to seat in the depression 14 formed in the felly band, there being slots 17 extending from the outside margin of the felly band to the annular depression 14 to permit of the insertion of the projections 16 carried by the rim. The walls of the depression 14 on either side of the slots 17 are inclined, so that when the said projections engage said inclined faces, there will be a tendency to move the rim against the inclined shoulders 12 and 13. This construction is in all particulars like the rim and rim flange shown in Fig. 5.

18 designates an inclined shoulder on the inner perimeter of the rim at the outside margin thereof, which engages against the shoulder 13, while at the inner margin of the rim opposite the shoulder 18 there is an inclined shoulder 19 formed by chamfering or beveling the rim to fit against the inclined shoulder 12.

20—21 designate depressions formed in the inner perimeter of the rim and the peripheral face of the felly band to receive a key 22 which prevents relative rotation between the rim and felly band. This key 22 is preferably secured to the felly by means of a bolt 23, and said key carries a hook 24 which facilitates its removal when the bolt is loosened.

The rim 15 has at its inside margin the usual flange 25, which is preferably formed integral with the rim, and whose cross section may vary according to the type of tire to be used therewith.

26 designates an integral extension of the

rim proper at its outside margin, which extension has its outer peripheral face, as shown in Fig. 2, beneath the inner peripheral face of the rim, there being between 5 said extension and the rim proper an inclined shoulder 27, and carried by said extension is a number of pins 28.

29 designates the removable rim flange which is preferably constructed of ring form 10 and of a cross section substantially that of the fixed flange 25. In the inner perimeter of the flange 29 there is a channel 30, the one wall of which is broken at intervals by slots 31 extending from the outside margin 15 of the flange to said channel, and the outer wall next adjacent said slots is provided with inclined faces 32 and the fixed stops 33, so that when the pins 28 are brought to engage with either of the inclined faces 32 20 there will be a tendency toward the crowding of the flange against the tire and also against the inclined shoulder 27. The channel 30 is interrupted at one point by a bridging lug 34 and the extension 26 of the rim 25 is provided with spaced apart internally threaded seats 35 at points adjacent the lug 34 to receive a set screw 36 which when placed in position will engage the lug 34 to 30 prevent rotation of the flange relative to the rim in one direction, while the pin 28 will engage with one or the other of the stops 33 and prevent rotation of the flange relative to the rim in the other direction.

In order to provide for the rotation of 35 the rim relative to the felly band, the felly band, as well as the felly, is slotted at 37, as clearly shown in Fig. 1, and through

these slots the valve stem 38 travels when moved, as just described. In order to close up said slots, I provide a plate 39 which is 40 perforated to receive the valve stem 38, and this plate is held in place by the valve cap 40, of ordinary construction. By providing the inclined faces 32 at each side of the slots 31, the rim may be used for either a right 45 or left hand wheel.

Formed in the outside margin of the removable rim flange 29 are the diametrically opposite seats 41, in order that a tool in the form of a bar may be placed in said seats 50 to rotate the rim flange relative to the rim as required in putting on or taking off a tire.

I claim:

In combination with a felly band having on its periphery spaced annular shoulders of different inclinations, the outermost shoulder having openings therethrough and which openings are chamfered at their inner ends, a rim having on its inner perimeter spaced annular shoulders inclined to correspond with the shoulders of the felly band, projections on said rim for insertion through said openings and to engage said chamfered inner ends thereof and means to prevent relative rotation of the rim and 60 felly band.

In testimony whereof, I have signed my name to this specification, in presence of two subscribing witnesses.

HENRY J. TRARES.

Witnesses:

E. L. WALLACE,
R. G. ORWIG.
